F. T. CLUGG.
WASHING MACHINE,
APPLICATION FILED JAN. 28, 1920.

Patented Apr. 26, 1921.

Inventor
F.T. Clugg

By A. Hanulsky, Atty

UNITED STATES PATENT OFFICE.

FLORENCE T. CLUGG, OF SPENCER, WISCONSIN.

WASHING-MACHINE.

1,376,255.

Specification of Letters Patent. Patented Apr. 26, 1921.

Application filed January 28, 1920. Serial No. 354,733.

To all whom it may concern:

Be it known that I, FLORENCE T. CLUGG, a citizen of the United States, residing at Spencer, in the county of Marathon and 5 State of Wisconsin, have invented certain new and useful Improvements in Washing-Machines; and I do hereby declare the following to be a full, clear, and exact description of the invention, such as will enable 10 others skilled in the art to which it appertains to make and use the same.

The present invention relates to washing machines, its principal object being to provide a washing machine having scrub 15 brushes or other cleaning elements supported therein for coöperation with the usual agitator in performing the washing operation.

A further object of the invention is to 20 provide a washing machine which includes a plurality of removable brushes or other cleaning elements which are arranged to permit one or more of the brushes to be removed when they become worn and new 25 ones substituted therefor.

Another general object of the invention is to provide a washing machine which is simple in construction, consists of few parts, and which may be manufactured and sold 30 at a minimum cost.

With the above and other objects and advantages in mind, the invention consists in the novel combination of elements, construction and arrangement, operation, and specific 35 features all of which may be enlarged upon and are explicitly defined in the appended claims.

On the drawing:

Figure 1 is a vertical sectional view of a 40 washing machine embodying my improvements;

Fig. 2 is a plan view of the machine having the cover removed;

Fig. 3 is a section taken along line 3—3 45 of Fig. 1, and

Fig. 4 is a bottom plan view of the central cleaning brush.

Referring in detail to the drawing wherein like characters of reference designate 50 like parts in all the views, the numeral 5 designates a receptacle provided with a removable lid 6. An agitator 10 is rotatably supported in the lid 6 and is rotated through the medium of a drive means desig-

55 nated as at 11. The agitator and the drive means form no part of the invention but

are shown for the purpose of illustrating the application of my invention.

The inner face of the side walls of the receptacle 5 is provided with a plurality of 60 parallel vertical dove tail grooves 12 in each of which removable brushes 13 are engaged. These brushes 13 are retained against longitudinal movement by set screws 14 carried by plates 15 mounted on the receptacle 5 65 and passing through the walls of the receptacle and fitting into sockets formed in the uppermost brushes.

The bottom of the receptacle is provided with a central opening 16 and extending 70 radially from this opening 16 upon the inner face of the bottom are a plurality of dove tail grooves 17 which extend to the outer edge of the bottom. Brushes 18 are insertible in these grooves from the inner 75 ends. The grooves 17 in the bottom do not register with the vertical grooves 12 and therefore the brushes 18 are out of alignment or disposed in staggered relation to the brushes 13. A circular brush 19 also 80 of scrub brush fiber and provided with a backing plate 19' is placed in the central opening 16 and is so disposed that the peripheral edge of the back of the brush engages the ends of the brushes 18 thus preventing 85 longitudinal movement of the same. A plate 20 is secured to the under face of the bottom of the receptacle by securing screws 21. This plate underlies the brush 19 and carries a set screw 22 which extends 90 through the center of the plate and into a threaded socket formed in the back of the brush to retain the brush in position. This plate also carries an upstanding pin 23 engageable in an opening 24 in the back of the 95 brush to retain the brush against rotation while the clothes are being cleaned.

From the disclosure it will be manifest that I have provided a washing machine wherein the scrubbing element may be readily removed from the receptacle when the same becomes worn and new ones substituted therefor.

The structure shown and described is a practical embodiment of the invention but 105 it will be understood that the same may be modified in many respects, and that such limits of modification are only governed by the subjoined claims.

What is claimed is:

1. A washing machine including a receptacle provided with an opening in the bot-

- tom thereof and further provided with dove tail grooves in the inner face of the bottom radiating from the opening and vertical dove tail grooves upon the inner face of the
5 walls of the receptacle, a brush removably engaged in each of the grooves, and a brush accommodated in the opening in the bottom and serving to retain the brushes in the bottom against movement in one direction.
10 2. The combination with a receptacle having a central opening in the bottom thereof and further provided with dove tail grooves which extend radially from the opening, the side walls of the receptacle also being
15 provided with the longitudinal dove tail

grooves positioned in staggered relation to the grooves in the bottom, cleaning elements insertible in the radially disposed grooves from the central opening, and a brush closing the opening, the edges of the 20 back of the latter brush abutting the inner ends of the radially disposed brushes, and brushes removably engaged in the grooves in the side walls of the receptacle.

In testimony whereof I affix my signature 25
in presence of two witnesses.

FLORENCE T. CLUGG.
